UNITED STATES PATENT OFFICE.

MICHAEL M. SCHERER, OF BATESVILLE, ARKANSAS.

COTTON-PRESS.

SPECIFICATION forming part of Letters Patent No. 257,079, dated April 25, 1882.

Application filed January 14, 1882. (No model.)

To all whom it may concern:

Be it known that I, MICHAEL M. SCHERER, of Batesville, in the county of Independence and State of Arkansas, have invented a new 5 and useful Improvement in Cotton-Presses, of which the following is a full, clear, and exact description, reference being had to the annexed drawings, forming part of this specification.

This invention relates to an improvement in 10 cotton-presses shown and described in Letters Patent No. 142,517, which were granted to me under date of September 2, 1873; and the invention consists in certain novel features of construction relating to different parts of the 15 press.

In the accompanying drawings, Figure 1 is a plan of my invention with the lint-room removed. Fig. 2 is a detail of the levers. Fig. 3 is a perspective of the press and lint-room, 20 with a side of the lint-room broken away; and Fig. 4 is a detail.

In the Letters Patent referred to I have shown a horizontal press having a follower, which is operated by means of toggle-levers, 25 and ropes connected thereto and adapted to be wound upon a windlass. In this press the levers, which are hinged to opposite sides of the press, so that their ends shall be brought nearly together by winding up the ropes attached to their ends, are constructed with stationary joints near the center thereof and provided with semicircular guides, over which they are made to pass when in operation. In my 30 present invention I have adopted a movable joint for the toggle-levers, consisting of a bolt, *a*, connected at its ends to two rods, *b*, which are attached to the follower *A* and a guide plate or plates, *c*, secured to the forward edge of the levers *B*, and provided with rods *d*, which 35 plates and rods are arranged parallel with each other and secured together, respectively, at the ends. The plates and rods extend from near the inner end of the levers to a point beyond the center, and to the bolt *a*, which is arranged 40 transversely between the plates and rods, is secured the rope *e*, which passes toward the inner end of the lever over a pulley, *f*, secured thereto, and back to the outer end of the lever over a pulley, *g*, secured thereto, whence it 45 passes to the windlass *C*. With this construction, when the press is in operation, the joints 50

are adapted to slide near the inner ends of the levers when the ropes are drawn, and thus by bringing the fulcrum of the lever near its fixed end the power of the press is greatly increased. 55

In the patent above referred to I have shown a lint-room having a vertically-sliding gravitating cover operated by means of a windlass, ropes, and pulleys. Instead of the sliding cover, the lint-room is covered with a stationary cover, 60 *i*, and it contains a vertically-sliding rotating table, *k*, which is adapted to be turned by means of a crank, *l*, attached to its axis, and to be raised or lowered by ropes attached to its axis, and passing over pulleys at the top of 65 the lint-room, and wound upon a windlass, *l'*, at the end of the lint-room. When the rotating table is at its lowest limit it is to be adjusted by bolts, in which position it forms the top of the space, in which the horizontally-mov- 70 ing follower *A* moves.

The cotton is received from the gin into the lint-room during the process of baling above the rotary table at *m*. When a sufficient amount of cotton is in the lint-room the rotary table 75 is raised and revolved half a revolution, whereby the cotton in the lint-room is thrown beneath into the space before the horizontal follower, by which it is pressed into a bale in the chamber *m'*. In this manner it is rendered 80 unnecessary to handle the cotton in making the bale, nor is it necessary to stop the gin during the process of baling. A suitable dust-flue, *n*, is formed at the top of the lint-room on the opposite end from the gin, whereby the 85 blast from the gin shall pass out of the lint-room, and thus carry out the dust. The levers are held in a horizontal position by means of chains or rods *o*, attached to the ends of a bar, *p*, across the top of the press, and to the levers 90 about one-third the distance from the outer end of the lever.

Having thus described my invention, what I claim as new, and desire to secure by Letters Patent, is—

1. In a cotton-press, the combination, with the follower *A* and the levers *B*, of the bolts *a*, guide-plates *c*, and rods *d*, inclosing said bolts, and the rods *b*, connecting the bolts with the said follower, and the ropes *e*, secured to the bolts *a* and passing over pulleys at the inner and outer ends of the levers, substantially 95 100

as shown and described, and for the purpose set forth.

2. In a cotton - press, the combination, with the levers B and the ropes e, passing over pulleys at the ends of the levers, of the rods b, connected to the follower at one end and to the ropes at the other, and forming sliding joints with the said levers, substantially as shown and described.

10 3. In a cotton - press, the combination, with the follower A and the follower - chamber, of

the lint-room placed above the follower-chamber and having a vertically-sliding rotary table, k, which forms the bottom of the lint-room and the top of the follower-chamber, and means 15 for operating the said table, substantially as shown and described.

MICHAEL MOSER SCHERER.
